CLAIM

I claim the ornamental design for an irrigation pivot wheel, as shown and described.

DESCRIPTION

FIG. 1 is a front view of an irrigation pivot wheel showing my new design;

FIG. 2 is a rear view of the irrigation pivot wheel of FIG. 1; FIG. 3 is a side view of the irrigation pivot wheel of FIG. 1; FIG. 4 is an opposite side view of the irrigation pivot wheel of FIG. 3;

FIG. 5 is a perspective view of the irrigation pivot wheel of FIG. 1;

FIG. 6 is an opposite perspective view of the irrigation pivot wheel of FIG. 5;

FIG. 7 is a front view of an alternative embodiment of an irrigation pivot wheel;

FIG. 8 is a rear view of the irrigation pivot wheel of FIG. 7; FIG. 9 is a side view of the irrigation pivot wheel of FIG. 7; FIG. 10 is an opposite side view of the irrigation pivot wheel of FIG. 7;

FIG. 11 is a perspective view of the irrigation pivot wheel of FIG. 7; and,

FIG. 12 is an opposite perspective view of the irrigation pivot wheel of FIG. 7.

The broken lines are for illustrative purposes only and form no part of the claimed design.

1 Claim, 10 Drawing Sheets
